CARTRIDGE CASE EJECTOR FOR RECIPROCATING BREECH BLOCK TYPE OF GUNS

Percy Reuben Higson, deceased, late of London, England, by Alice Matilda Higson, executrix, Sidcup, England, assignor to Vickers-Armstrongs Limited, London, England, a British company

Original application November 2, 1946, Serial No. 707,394. Divided and this application September 8, 1949, Serial No. 114,573. In Great Britain October 29, 1945

Section 1, Public Law 690, August 8, 1946
Patent expires October 29, 1965

4 Claims. (Cl. 42—25)

1

This invention relates to cartridge feeding and ejecting mechanism for machine guns of the type in which the breech block is reciprocated along the axis of the barrel and accommodates a relatively displaceable firing pin, for example, a machine gun of the type generally known as the "Vickers" type in which the firing pin is operated during the locking action of a side lever actuating the reciprocating breech lock, an example of this type of machine gun being shown in United States Patent No. 2,013,312. The object of the invention is to generally simplify and improve the feeding and ejecting mechanism and also to make sure that no empty cartridge case is left in the breech or on the breech block when the whole of the source of supply of the cartridges has been consumed.

In machine guns of the aforesaid type the breech block carries a relatively perpendicular guide with means adapted to receive the live rounds in succession from the supply source or magazine, this guide carrying a relatively reciprocating carrier member formed with an abutment adapted to engage the rim of each round so as to force the round into alignment with the firing pin, the carrier member being caused to negotiate an island type of cam for receiving its reciprocation during reciprocation of the breech block, the live round acted on by this abutment ejecting the empty cartridge case from the guide, and the invention is characterised in that the carrier member slidably supports a slide carrying a spring loaded ejector urged by its spring against the base of each live round taken from the magazine or ammunition supplying means of the gun so as to be ineffective upon the rounds until following the firing of the last available rounds and thereupon being urged by its spring into an operative position as an extension of the said abutment so that instead of a live round engaging and ejecting the empty cartridge case from the guide the said ejector member engages and ejects the cartridge case.

In order that the invention may be clearly understood and readily carried into effect, drawings are appended hereto illustrating an embodiment thereof, and wherein,

Figure 1 is a broken sectional side elevation of a Vickers machine gun breech mechanism in the firing position and embodying the present invention.

Figure 2 is a sectional side elevation showing the breech mechanism with the breech block in

2

fully recoiled position and with a round positioned ready for ramming into the breech,

Figure 3 is a sectional elevation of the breech in the firing position and firing the last round, and

Figure 4 is a sectional elevation showing the cartridge case of the last round being ejected.

Referring to the drawings the breech actuating and firing pin mechanism is shown by way of example as corresponding to that described in the co-pending Application Serial No. 707,394, now United States Patent No. 2,509,640, in which the firing pin 5 reciprocates within a cylindrical bore 6 of a breech block 1 having an abutment 2 co-operating with a sear 3, the breech block being reciprocated in known manner by a side lever 10 which as in co-pending Application Serial No. 707,394, now United States Patent No. 2,509,640, has an abutment 12 co-operating with an abutment 11 on the firing pin to automatically effect a striker action as the breech is closed. However, the present invention is more concerned with the means for transporting the cartridges from the feed box 18 to the breech and extracting and discharging the spent cartridge cases, the mechanism for this purpose being applied to the known form of upstanding guide 17 in which the cartridge indicated at C² is held by its rim in known manner between the flanges 17a of the guide. Following the withdrawal of a live round from the box 18 the round is urged along the flanges 17a simultaneously by the downward movement of a transporter member 15 in channel 16 in the guide 17, the transporter member having a lower front corner piece 15a which engages the rims of the rounds, thus ultimately bringing the appropriate live round into engagement with a spring loaded detent 4 (see Figure 2) in order that the cartridge may be located correctly at the front end of the breech block and supported in coaxial alignment with the barrel.

The reciprocating movement of the transporter member vertically relatively to the axis of travel of the breech block is controlled by an island type cam, i. e. spaced and opposed inclined cam surfaces 19, 19', 20 and 20', on a side plate 21 and top cover 22 respectively. That is to say the downward movement of the transporter member 15 is effected during the rearward travel of the horns 15' along the rear or descending part 19' of the upper cam surface, and also during the forward movement of the horns 15' along the

forwardly descending part 20' of the lower cam surface, the return or upward movement being derived from the cam or ramp surfaces 20.

When a round has been fired its case is withdrawn as the breech block is retracted, by reason of the interengagement of the cartridge case rim and the flanges 17a and in due course is ejected by the succeeding round forcing the empty cartridge case downwards over the detent 4.

Assembled to the said transporter member 15 is a spring loaded ejector 23 pivoted on a pin 24 to a slide 25 slidably supported by the transporter member for slight vertical reciprocation relatively to the transporter member 15, this ejector operating to eject the case of the last cartridge from the lower end of the flanges 17a when all of the ammunition has been consumed, and for this purpose the lower extremity of the ejector which, at the appropriate time engages the very last cartridge case, is located well in advance of the cartridge rim engaging part of the transporter 15. By "in advance" is meant that it leads the transporter part 15a when the transporter is moving downwards in the round feeding direction. The flanges 17a in effect forming a T-section slot in the guide 17 to receive the cartridge case rims. This ejector is deflected as shown in Figure 1 by the cartridge C¹ in the feed box, and is thereby caused to be inoperative until there is no cartridge in the belt when as shown in Figure 3, the ejector is urged slightly forward by its spring 26 and with the slide 25 is carried down with the carrier to its lowermost position as shown in Figure 4 to eject the cartridge case C² of the last fired cartridge over and beyond the aforesaid spring loaded detent 4. For this latter operation the front edge of the slide is formed with a recess 27 dimensioned to receive readily the ejector 23, the ejector comprising a finger pivoted to the slide and spring loaded forwardly as aforesaid by the coiled compression spring 26, the arrangement being such that the lower part of this ejector is prevented from moving forwardly under the influence of such spring by reason of its engagement with the base of the appropriate cartridge C¹ in the feed box, but following the removal of the last round in the feed box the ejector 23 is free to move forwardly on its pivot so that its lower end bears against the uppermost point of the base of the cartridge case and pushes such case downwardly beyond the spring loaded detent. Excepting when the last cartridge case is to be ejected the ejector 23 is prevented from being pressed forwardly by its spring 26 when the cartridge is positioned (as in Figure 2) in the loading position, by the lower edge of this ejector abutting against a step 28 on the front end of the breech block, thus causing the ejector to be pushed upwards relatively to the carrier so that the lower part of the ejector lies behind the round engaging corner piece 15a of the transporter member. The extractor is formed with a recess or step 23a adapted to slip over the corner piece 15a when the extractor comes opposite the empty feed box 18 (see Figure 3) so that it cannot now be moved upwardly relatively to the slide 25 and forms a positive abutment to engage and eject the last cartridge case as in Figure 4.

I claim:

1. In a "Vickers" type machine gun, the combination of a breech and barrel, a reciprocating breech block, a side lever actuating the breech block, a firing pin in the breech block operated

5 from the side lever, a cartridge supply compartment above the breech, a cartridge guide carried by and upstanding from the breech block, a cartridge transporter reciprocating vertically along said guide, means imparting vertical reciprocation to the transporter during reciprocation of the breech block, a cartridge rim engaging part with said transporter which engages and extracts the rounds in succession from said compartment and pushes each extracted round down the said guide on to the breech block and presses the extracted live round against the empty cartridge case carried by the breech block to eject the empty cartridge case, an ejector member 10 connected to the transporter member and having in advance of the rim engaging part of the said transporter member its own distinctive cartridge rim engaging part extending therefrom to engage and eject the empty cartridge case from the breech block when the supply of ammunition is exhausted, means yieldingly opposing rearward displacement of the ejector member so that the ejector member is held in an inoperative position in rear of the cartridge engaging part of the transporter member by the base of the live round engaged by the transporter member, said means urging the ejector member into an operative position with its cartridge rim engaging part located in advance of the like part of the transporter member to act as a substitute for a live round to engage and eject the empty cartridge case from the gun.

2. A machine gun according to claim 1 wherein the breech block is formed at its leading end with a spring loaded plunger having its leading end located so as to serve as an abutment for positioning the rounds in operative alignment with the firing pin, said plunger being pressed into the breech block under the influence of the downward pressure of the empty cartridge case being ejected.

3. A machine gun according to claim 1 wherein said ejector is relatively translatively slidably connected to the transporter member and the breech block is formed with an abutment part engaged by the leading end of the ejector during the completion of the feeding of a round into alignment with the breech by the transporter member to cause a displacement of the ejector to an idle position abutting against the rear of the round engaging part of the transporter during return of the transporter from the breech.

4. A machine gun according to claim 3 wherein the ejector is pivoted to a slide slidably within the transporter member and a spring between said slide and the ejector urges the ejector to the operative position to engage the rim of the very last empty cartridge case.

ALICE MATILDA HIGSON,
60 Executrix of the estate of Percy Reuben Higson,
deceased.
